UNITED STATES PATENT OFFICE.

WILLIAM A. PROCTOR, OF AMESBURY, MASSACHUSETTS.

WINDSHIELD REGULATOR.

Application filed September 29, 1925. Serial No. 59,358.

This invention relates to devices used in connection with automobile bodies for locking windshields in various positions of swinging adjustment and more particularly to certain improvements on the construction illustrated in my Patent No. 1,652,638, December 13, 1927.

In the construction of my said application, difficulty has been encountered in so installing the device that the clamping action on both brackets at the ends of the wind shield would be uniform, and it is considered that the extreme accuracy of adjustment required for its satisfactory operation would be difficult to secure, particularly where quantity production and installation is desired, and in an apparatus of the above described character, it is desirable for the workman to be able to make the installation with the use of common tools and without the necessity of drilling.

The objects of my invention are to provide a construction embodying all the practical advantages of my said prior construction, which is adapted to be produced and furnished for installation in such a form that it may be readily installed, and at the time of installation, may be readily and accurately adjusted, so that, when the clamping means is operated, the shield will be firmly clamped at each end to the fixed brackets.

I accomplish these objects by means of the construction illustrated in the accompanying drawings, in which:

Fig. 1 is a sectional view at line $\alpha-\alpha$ of Fig. 2.

Fig. 2 is a front elevation, partly broken away, of the complete device embodying my present invention.

Fig. 3 is an enlarged detail view of one end portion of the device, in longitudinal central section.

Fig. 4 is a front elevation of a construction embodying a generic form of my invention.

Fig. 5 is a longitudinal central sectional view thereof.

Figs. 6 and 7 are side elevations thereof showing closed and open positions of the shield.

In the drawing, 1 indicates the body, window casing or other fixed supporting means, having a front opening, and 2 a wind shield, or screen adapted and arranged to close said opening; said shield being adjustably mount-

ed on the body to swing about a pivot 3 at each end, and at its upper edge, from a nearly vertical position, in which the opening will be fully closed thereby and forwardly to various more or less open positions.

According to my present invention I provide a pair of brackets 4, which are rigidly fixed in vertical positions on the body, or casing, about the shield opening, one bracket being arranged at each end of the opening, and said brackets being preferably formed of stiff sheet metal, having slight resiliency, and being secured to the body at one edge in any suitable manner, as by ears 4'. Said brackets are arranged to project rearward from the casing in planes perpendicular to the axis about which the shield 2 swings, and each bracket has an arc shaped slot 5 formed therein, the edges of which are concentric with the axis of the shield, oppositely disposed clamping faces being provided at each side of the slots.

A pair of metal arms 6 are fixed on the shield at each end thereof, at a short distance below its pivotal supports and closely adjacent the inner, or adjacent sides of the brackets 4, respectively, said arms extending, when the shield is in closed position, rearwardly and then upwardly in an oblique direction to points adjacent the upper ends of the brackets 4. The arms 6 are each provided with a screw threaded aperture in the end portions thereof, said apertures being arranged in central alignment and in such a position that their line of centers intersects an arc which is concentric with, and midway between the sides of the slots 5 of the brackets, as indicated in Fig. 1. The aperture, in the arm 6 at the right end of the shield is provided with a left thread and, that in the arm at the left with a right thread, and a straight tube 7 is provided, which has corresponding external right and left threads at its ends, which are respectively screwed into the corresponding arms 6, so that, when the tube is rotated in one direction, the arms 6 will be sprung away from each other and when it is rotated in the opposite direction they will be sprung towards each other. A handle 8 is mounted on the tube at any convenient intermediate point and is firmly secured thereto, as indicated.

A rod 9 is extended thru the tube 7 and beyond the ends thereof, the end portions of the rod being respectively located in the

slots 5 of the adjacent brackets and being extending beyond the opposite or outer sides of the brackets to a sufficient extent to receive nuts 10, which are threaded thereon.

When installing the device, the nuts 10 are screwed onto the end portions of the rod until the faces of the nuts are held in close proximity to the adjacent faces or sides of the brackets, but normally do not positively engage the same. The sides of the arms about the apertures therein, and next to the adjacent brackets, form clamping faces, which are adapted to be engaged with the adjacent faces of the brackets at each side of the slots therein. Under normal conditions the faces on the arms are also disengaged from the brackets, as indicated in the full line position of Fig. 3. Under these conditions the shield may be readily swung on its pivots, or adjusted to any position to which it is adapted for adjustment, the rod 9 being moved in the slots 5, as the shield is swung.

When it is desired to lock the shield in any position to which it may have been adjusted, the tube 7, by means of the handle 8, is turned to the right, so that both end portions thereof are unscrewed from the arms 6 in which they are threaded, and, as a result, the end portions of the arms are sprung towards the brackets adjacent thereto until they engage the same and then, on further rotation of the tube, the brackets will be sprung apart until their outer sides engage the faces of the nuts 10, as indicated in the dotted line position of Fig. 3, and, when the tube has been turned to the right as far as possible, each bracket will be firmly clamped between the nut and arm at each side thereof, so that each arm will thus be firmly locked to its adjacent bracket, locking the shield in its adjusted position. To unlock the shield so that it may be adjusted, it is merely necessary to turn the tube 7 to the left, so as to permit the arms to spring away from the brackets and the brackets to spring away from the nuts 10. It is to be noted in this connection that, as the nuts are connected by the rod 9, which is adapted to slide longitudinally in the tube 8, the clamping action cannot take place at one end of the shield without taking place at the opposite end, and that both arms are clamped simultaneously to the brackets with equal force. Also, that, after the nuts 10 have been adjusted on the rod, so that the distance between their face ends is only slightly greater than the distance between the opposite faces of the brackets, further adjustment thereof is unnecessary, and the nuts may be locked in position on the rod by upsetting the ends of the rod, or in any other suitable manner, and become fixed abutments on the rod.

This arrangement is advantageous as it enables the device to be attached and ad-

justed readily to different conditions, due to slight variations in the relative positions in which the arms are attached to the shield and the brackets to the casing, the tube being adjustable in the arms and the nuts being likewise adjustable on the rod, to a sufficient extent to provide for all usual conditions, it being understood that the lengths of the rod and tube will be adapted to the particular construction to which the device is to be applied. The parts may then be adjusted so that they may be moved between a locked and an unlocked position by a very slight portion of a turn of the tube, and the clamping action on each bracket will always be the same. That is, the adjustment may be such that, in the unlocked position, the adjacent faces of the arms and brackets may be in sliding contact, provided the frictional engagement therebetween is insufficient to interfere with the ready adjustment of the wind shield. The advantages, so far as the facility of adjustment and of locking and unlocking, by means of a single handle, are concerned, are the same as with my said prior construction.

A modified form of my generic invention may be employed in connection with a single bracket and locking means located at the middle of the shield, where the advantages of a lock at both ends of the shield are not desired, as shown in Figs. 4 to 7.

In this form, I preferably provide a pair of parallel arms 11 and 12, which are formed integrally with a base 13, the latter being attached to the middle upper portion of the frame 14 in which the glass of the shield 2 is mounted, and a bracket 15 is mounted on the casing close to the opposite side of the arm 11 from arm 12, said bracket 15 being similar in all respects to the brackets 4 previously described and being provided with an arc shaped slot 16 having as its center the axes of the shield frame 13, which is mounted on pivots 22. The arms 11, 12 have aligned apertures in their ends, which also align with the slot 15, and a tube 17 is provided which is threaded into the aperture of the arm 11 at one end and abuts at its opposite with the adjacent side of the arm 12. A bolt 18, having a head 19, is passed thru the arm 12, tube 17 and slot 16 and a nut 20 is threaded on the opposite end of the bolt and screwed thereon to such a point that the head 19 will be engaged with the adjacent side of the arm 12 when the face of the nut is in close proximity to the side of bracket 15. A handle 21 is mounted on the tube 17 and rigidly secured thereto. When the frame is adjusted on its pivots 16 the bolt 18 moves in the slot 16 as indicated in Figs. 6 and 7.

With this construction the locking action is similar to that in the construction first described. As the tube 17 abuts against the

arm 12, when the tube is turned in a direction to unscrew the same from arm 11, the arms will be sprung away from each other pressing the arm 11 against the adjacent 5 side of the bracket 15 and pressing the arm 12 against the head 19 of the bolt 18 and acting to draw the nut 20 thereon against the opposite side of the bracket, so that the bracket will be clamped between the arm 10 11 and nut 20, thereby locking said arm 11 to the bracket.

In this connection, it is to be noted that, if the arm 12 was so constructed that it yielded to lateral strain less readily than 15 the arm 11 and bracket 15, then, in securing the locking action, the arm 11 would first yield and then press the bracket against the nut 20, which would be unyieldingly held by the arm 12 thru the bolt 18 and head 19. 20 In practice a combination of both actions takes place, as the arm 12 will usually yield slightly, altho the actual lateral movement of the parts is practically imperceptible to the eye. The principal function of the arm 25 12 is to provide a support for the handle at each end, and the clamping action would be practically the same if the head 19 were directly engaged by the adjacent end of the tube 18, instead of indirectly engaged thru 30 the arm 12. This construction would only be used where a clamp at each end of the shield was not necessary and does not possess the more important advantages of the 35 construction first described, as compared with the construction of my said pending application.

I claim:

1. In combination with a support having a wind shield pivotally mounted thereon, an 40 arm mounted on and extending at one side of said shield, said arm having a side face disposed in perpendicular relation to the pivotal line of the shield, a handle screw threaded at one end in said arm and disposed at the opposite side thereof from said 45 face, a bracket mounted on said support and having a face at each side disposed in parallel relation to the face of said arm, with its face adjacent thereto in position 50 for engagement with the face of said arm in all positions of the shield, and means arranged for simultaneous engagement with said handle and with the other face of said bracket in all said positions to cause the adjacent faces of said arm and bracket to be 55 forced into engagement, on rotation of the handle to move it away from the bracket, and to lock the shield in the position to which it is adjusted.

2. In combination with a support having a wind shield pivotally mounted thereon, an 60 arm mounted on and extending at one side of said shield, said arm having a side face disposed in perpendicular relation to the pivotal line of the shield, a handle screw 65

threaded at one end in said arm and disposed at the opposite side thereof from said face, a bracket mounted on said support and having a face at its side next said arm disposed in parallel relation to the face 70 thereof and in close proximity thereto in all positions of the shield, and means arranged for simultaneous engagement with said bracket and said handle, in all said positions, to force said arm and bracket into engagement on rotation of the handle to move it away from said bracket, to lock the shield in the position to which it is adjusted. 75

3. In combination with a support having a wind shield pivotally mounted thereon, an 80 arm mounted on, and extending at one side of said shield, and having a side face disposed in perpendicular relation to the pivotal line thereof, a handle screw threaded at one end in said arm at the opposite side 85 thereof from said face and in perpendicular relation thereto, a bracket mounted on said support and having a face at each side disposed perpendicularly and concentrically with relation to the pivotal line of the 90 shield, with one face thereof in close proximity to the face of said arm and means arranged for simultaneous engagement with the other face of the bracket and with the handle to spring said arm and bracket together, on movement of the handle to unscrew it from the arm and to force their 95 adjacent faces into locking engagement.

4. In combination with a support having a wind shield pivotally mounted thereon, an 100 arm mounted on, and extending at one side of said shield, and having a side face disposed in perpendicular relation to the pivotal line thereof, a handle screw threaded at one end in said arm at the opposite side 105 thereof from said face and in perpendicular relation thereto, a bracket mounted on said support and having a face at each side disposed perpendicularly and concentrically with relation to the pivotal line of the 110 shield, with one face thereof in close proximity to the face of said arm, and a rod arranged for engagement with said handle and with the other face of said bracket, whereby, on movement of the handle to unscrew the same from said arm, said rod 115 will be actuated longitudinally to cause relative lateral movement of said arm and bracket to bring their adjacent faces into locking engagement. 120

5. In combination with a support having a wind-shield mounted for swinging adjustment thereon, an arm fixed on said shield and extending to one side thereof, a handle for adjusting said shield mounted for rotation in said arm at one end and having a screw threaded connection therewith, a bracket fixed on said support and extending perpendicularly to the said axis of the 125 shield, said bracket having oppositely dis- 130

posed faces extending concentrically of said axis, and arranged at the opposite side of said arm from said handle with its adjacent face in close proximity to the adjacent side of the arm, and a rod extending axially thru said handle from end to end thereof and thru said arm to the opposite side of said bracket and having abutting means at each end arranged for engagement at one end with the face of said bracket opposite from said arm and at the opposite end by the adjacent end of the handle.

6. In combination with a support having a wind-shield mounted for swinging adjustment thereon, an arm fixed on said shield and extending to one side thereof, a handle having a screw thread connection at one end with said arm and rotatable therein about an axis parallel to the axis of the shield, a bracket fixed on said support at the opposite side of said arm from said handle and having oppositely disposed faces extending perpendicularly to said axis and concentrically thereof, with the face next said arm in close proximity to the adjacent side of the arm and a rod extending axially thru said handle from end to end thereof and thru said arm to the opposite side of the bracket therefrom, said rod having an abutment at each end, one arranged to engage the face of the bracket opposite from the arm and the other arranged for engagement by the opposite end of the handle from said arm.

7. In combination with a support having a wind-shield mounted for swinging adjustment thereon, a pair of arms fixed on the shield and extending to one side thereof, a handle disposed between and mounted for rotation in said arms at the ends thereof, a means connected to said handle having a threaded connection with one of said arms and engaged with the other arm, whereby, when the handle is rotated in one direction, said arms may be sprung apart, a bracket mounted on said support and having oppositely disposed faces extending concentrically with, and perpendicularly to said axis with one of said faces disposed in close proximity to the side of one of said arms opposite the handle, and a rod having an abutment at each end respectively arranged to engage the other of said arms and the side of the bracket opposite therefrom when said handle is rotated to spring said arms apart, thereby to force said arm and the adjacent face of said bracket into locking engagement.

8. In combination with a support having a wind-shield mounted for swinging adjustment thereon, a pair of arms mounted on said shield adjacent each end and extending to one side of the axis of the shield, a tube mounted for rotation in the end of said arms and having opposite screw thread connections therewith, a handle on said tube for

moving it laterally to adjust the shield and rotatably to spring said arms to or from each other, a pair of brackets mounted on said support at the opposite sides of said arms, in close proximity thereto, and having oppositely disposed faces extending perpendicularly to, and concentrically with the axis of the shield, and a rod extending thru said tube and having an abutment at each end arranged to engage the faces of said brackets opposite said arms, whereby, when said arms are sprung apart, said brackets will be clamped between the corresponding arms and abutments.

9. In combination with a support having a wind-shield mounted for swinging adjustment thereon, a pair of arms mounted on said shield adjacent each end and extending to one side of the axis of the shield, a tube mounted for rotation in the ends of said arms and having opposite screw thread connections therewith, a handle on said tube for moving it laterally to adjust the shield and rotatably to spring said arms to or from each other, a pair of brackets mounted on said support at the opposite sides of said arms in close proximity thereto and having oppositely disposed faces extending perpendicularly to, and concentrically with the axis of the shield, and a rod extending thru said tube and having an abutment at each end arranged to engage the faces of said brackets opposite said arms, one of said abutments being arranged for relative adjustment on the rod according to the distance between the faces of the brackets adjacent thereto.

10. In combination with a support having a wind-shield mounted for swinging adjustment thereon, a pair of arms mounted on said shield adjacent each end and extending to one side of the axis of the shield, a tube mounted for rotation in the ends of said arms and having opposite screw thread connections therewith, a handle on said tube for moving it laterally to adjust the shield and rotatably to spring said arms to or from each other, a pair of brackets mounted on said support at the opposite sides of said arms, in close proximity thereto, and having slots therein extending concentrically with the axis of the shield and oppositely disposed faces adjacent said slots extending perpendicularly to said axis, and a rod extending thru said tube and arms and having its end portions disposed in said slots, said end portions having abutting means for engaging the faces of said brackets opposite said arms and means permitting relative adjustment thereof according to the distance between said faces.

In testimony whereof, I have signed my name to this specification.

WILLIAM A. PROCTOR.
